UNITED STATES PATENT OFFICE.

ISAAC S. DEMENT, OF EAST ORANGE, NEW JERSEY, AND FOSTER J. HULL, OF BROOKLYN, NEW YORK, ASSIGNEES, BY MESNE ASSIGNMENTS, TO AMERICAN MECHANICAL CASHIER COMPANY, A CORPORATION OF NEW JERSEY.

REGISTER

No. 818,234.

Specification of Letters Patent.

Patented April 17, 1906.

Application filed March 20, 1902. Renewed December 7, 1905. Serial No. 290,751.

To all whom it may concern:

Be it known that we, ISAAC S. DEMENT, residing at East Orange, Essex county, New Jersey, and FOSTER J. HULL, residing at Brooklyn, Kings county, New York, citizens of the United States, have invented certain new and useful Improvements in Registers, of which the following is a specification.

This invention relates to improvements in registers; and one of its objects is to provide for carrying or accumulating from lower to higher denominations by the direct action of an operating device on the registering device, which is to be moved so as to avoid the friction and uncertainty arising from operation of higher-denominational devices through the lower ones.

A further object of the invention is to provide for establishing connection between the said operating means and the register devices whenever it is desired to operate the latter.

Referring to the accompanying drawings, which form a part of this specification, Figure 1 is an end view of a register embodying our invention, part of the keyboard-frame being broken away. Fig. 2 is a plan view of the same, a part of the keyboard mechanism being removed and the register-connecting mechanism being shown in operative position. Fig. 3 is a vertical section from front to back. Fig. 4 is an end elevation of the keyboard mechanism, register, and controlling devices. Fig. 5 is a vertical section of the keyboard mechanism on the line A A in Fig. 2. Fig. 6 is a front view of the register mechanism. Figs. 7 and 8 are longitudinal sectional views on the line B B in Fig. 2 of the controlling mechanism and the carrying or accumulating devices therein. Fig. 9 is a plan view of a register-operating shaft, and Fig. 10 is a longitudinal section thereof. Fig. 11 is a longitudinal section of the register end of the highest-denomination shaft. Fig. 12 is a detail view of a transmitting means for an extra counting-wheel. Fig. 13 is a detail view of a resetting rack-bar. Fig. 14 is a plan view of an engaging or connecting means for the register, showing its normal position. Fig. 15 is an under side view of the resetting devices. Fig. 16 is a horizontal section of the operating means for the register cut-off or disengaging device.

The parts are mounted on a suitable frame

1 and may be associated with any suitable recording mechanism and, if desired, with a 55 cash-changing mechanism.

A keyboard mechanism, comprising keys 2, tumblers 3, engaged by said keys, and slides 4, operated and locked by said tumblers, controls the release and arrest of sliding controller-bars 5, which are driven in one direction by springs 6 and operated in the other direction by resetting means, the slides 4 being arranged in groups corresponding to the denominational groups of keys and all the 65 slides of each group engaging one of the latches 7, which normally holds the controller-bar 5 from movement. When any key is depressed, it turns the corresponding tumbler 3, which presses on a lug of slide 4 to 70 move said slide backward, thereby disengaging latch or detent 7 from the controller-bar 5 corresponding to that group, which bar then moves under the influence of its spring until it is arrested by striking the projected 75 slide-bar 4. All these parts are substantially as shown and described in our application, Serial No. 75,948, filed September 20, 1901.

Each controller-bar 5 has a rack 9 (see Figs. 2 and 7) engaging a pinion 10 on a 80 shaft 11, operating the register. This shaft is hollow and carries at its forward end a ratchet wheel or head 12, engaged by a pawl 13, sliding longitudinally in a loose head 14, sliding on the register-shaft 15, which is in 85 line with the shaft 11, a pin 14' on said head sliding in a hub on said shaft, so as to cause these parts to turn together. The register-wheel 16 and its star-wheel 17 for causing accurate positioning thereof are fast on shaft 90 15. Pawl 13 is pressed into engagement with ratchet-head 12 by a spring 13', and a spring 19 normally presses the sliding head 14 away from the ratchet-head. Under certain conditions, however, the head 14 is held 95 toward the ratchet-head, so as to cause the shafts 11 15 to be connected by the ratchet connection 13, this being effected by a bar 20, (see Fig. 14,) supported on parallel-motion links and engaging with the front of heads 14, 100 this bar being operated by means hereinafter described.

From each register-shaft 15, except that for the highest denominations, a rod 21 passes back through the hollow shaft 11 and carries 105 near its rear end a lug or arm 22, that serves

to determine the operation of the carrying means, hereinafter described.

To reset the controller-bar 5 to the original position, a series of rack-bars 23 (see Figs. 7, 13, and 15) are provided, that slide in a frame-support 1' and are driven in one direction by springs 24 and have lugs 23' 23'' straddling the corresponding bars 5, and one of said lugs engages a lever 25, pivoted on and connected by spring 25' to the corresponding controller-bar 5, so that as the said rack-bar 23 is moved in the direction of the arrow in Fig. 8 the lug 23'' engages said lever and will pick up and drive in said direction any of the controller-bars that may have been operated, the spring 25' being strong enough to overcome the action of the controller-bar springs 6. Rack-bars 23 are operated by mutilated pinion 29 on a shaft 30, that is connected by bevel-gears 31 and chain 32 with the operating-handle 33 in obvious manner.

The carrying or accumulating means comprise a plate or dogging device 34, arranged alongside of each controller-bar 5, except the one of lowest denomination, and resting normally in the position shown in Fig. 7, with a lug or tooth 35 on the lower side thereof on one side of a double incline or shoulder on the top of a stop-plate 36, fixed in position in the machine-frame. Another lug 37 on this plate 34 engages with the other side of said stop-plate, a third lug 38 engages under and back of an incline or lug 39 on the corresponding controller or rack bar, and a fourth lug 40 is engaged by the arm or lug 22 on the register-shaft of next lower denomination.

Normally the racks 23 are out of engaging relation with the pinion 29, being pulled over by springs until lug 23' engages the ends of corresponding dogging-plates 34 and press the lugs 37 thereon against the stop-plate 36. When the handle is turned, the pinion 29 is rotated into engagement with the racks 23 and carries the same in the direction of the arrow in Fig. 8 until finally the cut-away part of the mutilated pinion is reached, whereupon the springs 24 pull the bars 23 back to normal position. The cut-away parts of the pinion 29 are arranged in different angular positions, so as to release the racks 23 consecutively or successively. The operation of the registering and carrying mechanism as above described is as follows: Keys having been depressed to set or project certain slides in certain of the denominational groups and the controller-bars having been thereby released and thrown over by their springs until they are arrested in corresponding positions without moving the register on account of the pawl-and-ratchet connection 12 13, the operator turns the handle, thereby driving all rack-bars 23 in direction of the arrow in Fig. 8 and picking up and resetting all of the controller-bars and setting the register forward corre-

spondingly. The dogging-plate has, however, been held by its lug 37 from following the controller-bar in its spring-actuated movement, and when the controller-bar approaches in its return to normal position its hook, lug, or incline 39 comes over the lug 38 on this plate and prevents the latter from rising, and also at the same time stops the movement of the controller-bar itself. If, however, the next lower denomination has during this particular operation passed the zero or tens point, the arm or lug 22 on the lower shaft will engage the dogging-plate 34 and press same endwise, so as to lift and slide the dogging-plate over the shoulder 36. Then when the controller-bar 5 is reset, which on account of the different angular position of the release portions of the resetting-pinions will not be until after the operation of the next lower shaft, the lug or incline 39 thereon does not engage the lug 38; but the controller-bar is allowed to move one step farther until a part of said bar (shown at 5^a, Figs. 7 and 8) engages the stop-plate 36. The corresponding register-wheel is thus moved one step farther to "carry one" from the next lower denomination. Then as the corresponding reset-rack 23 slips off its pinion spring 6 quickly drives controller-bar 5 back to its normal position, with its shoulder 5' (see Fig. 8) resting against the detent-latch 7, and thus withdraws hook 39 sufficiently from lug 38 to enable the reset-bar 23 by its lug 23' to press the dogging-plate 34 back to normal position, its tooth riding over the inclined top of plate 36. As the reset-racks 23 must be given sufficient movement to provide for the extra movement of the controller-bars, the yielding intermediate device 25 is required, so as to enable the controller-bars to be normally arrested short of this maximum movement without interfering with the further movement of the reset-rack.

To operate the engaging or clutch means for the register, a handle or thumb-piece 43 is provided, having fast on its shaft a pinion 44, engaging a rack-bar 45. A pin 45' on said bar engages with a lever 46, to which is pivoted a pusher-plate 47, riding on a fixed frame-plate 1" of the register and engaging when moved in one direction with the end of retaining-bar 20, above referred to, to connect the register in operative relation. The normal position of this handle or thumb-piece is such that the rack-bar holds pusher-plate 47 away from bar 20 to allow the springs 19 to move the heads 14 away from ratchet-wheels 12 and cut off the operative connection of the register. When the rack-bar 45 has been moved by thumb-piece 43 to cause connection of the clutch device and the reset-shaft 30 is subsequently operated, a lug 50, Fig. 14, in said shaft engages a projection 45" from said rack-bar to restore the bar to normal position and disconnect the register. A pin 48.

sliding in the pinion 44, is pressed by spring 48' into engagement with a notch 49 (see Fig. 16) in the fixed frame-plate 1" when the parts are in normal position. When the thumb-piece or handle 43 is shifted in the opposite direction to that above described, this pin rides out of said notch, and its other end is thereby caused to project beyond the pinion-body into the path of the lug 50 on the reset-shaft 30, so that in the next operation of the main handle 33 this lug 50 will strike the pin 48 and turn the pinion, rack, and thumb-back to normal position, whereupon the pin 48 will snap into the notch 49 and hold the parts in position by frictional resistance.

A series of recorder-bars 51 are shown engaging the pinions 52 on the controlling-shafts 11, so as to be shifted in accordance with the movement of said shafts under the control of the keyboard, said bars being provided with type and a platen or hammer impression means 53 being provided to coöperate with such type. The bar 45 above referred to serves also as a recording-bar, being provided with special type or marks indicating the kind of purchase—for example, "Paid," "Ex.," (exchange,) "C. O. D.," &c. Normally the bar may be in position to print the mark "Exchange" and the register is disconnected; but if the thumb-piece be turned to bring the mark "Paid" into position to be printed the pusher-plate 47 will engage with the retaining-bar 20 and the register will be connected until the bar is reset by lug 50 engaging with a projection 45". On moving the bar 45 in the other direction for marking other special kinds of purchase the register will remain disconnected and the bar will be reset by lug 50 engaging with pin 45.

Register-shaft 15 of highest denomination connects by one-toothed gear 55 and gear-wheel 56 (see Fig. 12) with a wheel 57, Fig. 6, that carries the summation one or more denominations higher. To give a greater accumulative capacity for a single wheel, the wheel 57 is provided with two circumferential rows of numerals, one consisting of two series of consecutive digits, zero to nine, and the other of a series of zeros and a series of ones. Holes (indicated by dotted lines 59) in front of the respective rows enable both rows to be read simultaneously, the rotation being such as to first read a zero of the second row, followed by a digit of the first row, and then when nine is passed reading one in the second row followed by a digit in the first row.

Having thus described our invention, what we claim as new therein, and desire to secure by Letters Patent, is—

1. The combination of a plurality of registering devices of different denominational value, a plurality of operating means for the respective registering devices, pawl - and - ratchet connections between the operating means and the registering devices, and means

controlled by the registering devices to limit the movement of the operating means for the registering devices of higher denominations and for allowing extra movement of such operating means when the lower registering devices pass the zero-point.

2. The combination of a plurality of register-shafts a plurality of operating shafts, sliding controller-bars, geared to said operating-shafts, dogging means for limiting the movement of said controller-bars and means connected to the register-shafts to control operation of such dogging means for the controller-bars of next higher denomination.

3. The combination of a plurality of register-shafts, a plurality of operating-shafts connected thereto by pawl-and-ratchet connections, sliding controller-bars, geared to said operating-shafts, dogging means for limiting the movement of said controller-bars and means connected to the register-shafts to control operation of such dogging means for the controller-bars of next higher denomination.

4. The combination of a plurality of register-shafts, a plurality of operating-shafts connected thereto by pawl-and-ratchet connections, controller-bars geared to said operating-shafts, springs for moving said controller-bars in one direction, keyboard mechanism for determining the extent of said movement, handle-operated reset mechanism for moving said bars in succession in the opposite direction, dogging devices for the controller-bars determining the extent of their reset movement and means operated by the register-shafts to release said dogging means for the controller-slides of next higher denomination when the said register-shafts pass the zero-point.

5. The combination of a plurality of register-shafts, a plurality of operating-shafts connected thereto by pawl-and-ratchet connections, controller-bars geared to said operating-shafts, springs for moving said controller-bars in one direction, keyboard mechanism for determining the extent of said movement, handle-operated reset mechanism for moving said bars in succession in the opposite direction, dogging devices for the controller-bars, fixed stopping means coöperating with said dogging devices for determining the extent of the reset movement, and means operated by the register-shaft to release said dogging means by pushing it over said stopping means, for the controller-slides of next higher denomination when the said register-shafts pass the zero-point.

6. The combination of a plurality of register-shafts, operating-shafts connected thereto by pawl - and - ratchet connections, controller-bars geared to said shafts, keyboard mechanism and operating means controlling the movement of said controller-bars in one direction, reset means for moving said bars in reverse direction, fixed stopping means and

- dogging devices for the controller-bars and engaging normally with one side of said fixed stopping means and means connected to the respective register-shafts for pushing said dogging devices to the next higher denomination over the said fixed stopping means when the said register-shafts pass the zero-point.
7. The combination of a plurality of register-shafts, a plurality of operating-shafts connected thereto by pawl-and-ratchet connections, controller-bars geared to said operating-shafts, springs for moving said controller-bars in one direction; keyboard mechanism for determining the extent of said movement, handle-operated reset mechanism comprising a yielding connection for moving said bars in succession in the opposite direction, dogging devices for the controller-bars determining the extent of their reset movement and means operated by the register-shafts to release said dogging means for the

controller-slides of next higher denomination when the said register-shafts pass the zero-point.

25

8. The combination of the rack-bars of a registering device and a resetting device, provided with engaging parts capable of being disengaged from each other when the resetting device has moved the registering device back to its normal position.

30

9. The combination with a plurality of registering devices and their operating means, of pawl-and-ratchet connections between said parts having members slid able into and out of engaging relation and means engaging the said slid able members to disconnect the registering devices.
